UNITED STATES PATENT OFFICE.

JOHN H. M. NIEMANN, OF CHAMOIS, MISSOURI.

SHOCK-LOADER.

No. 851,203.

Specification of Letters Patent.

Patented April 23, 1907.

Application filed May 5, 1906. Serial No. 315,407.

To all whom it may concern:

Be it known that I, JOHN H. M. NIEMANN, a citizen of the United States, residing at Chamois, in the county of Osage and State 5 of Missouri, have invented certain new and useful Improvements in Shock-Loaders, of which the following is a specification.

The purpose of the present invention is to devise an attachment which may be readily 10 applied to the ordinary farm wagon to admit of the same being utilized for lifting, transporting and depositing shocks of grain or like load which may be required to be lifted, moved and again placed upon the 15 ground in an upright position.

The invention contemplates, essentially, an attachment which may be readily fitted to and detached from the running gear of the accustomed farm wagon, thereby admitting 20 of the latter being used for general purposes and when required to be readily adapted for loading shocks.

For a full description of the invention and the merits thereof and also to acquire a 25 knowledge of the details of construction of the means for effecting the result, reference is to be had to the following description and accompanying drawings.

While the invention may be adapted to 30 different forms and conditions by changes in the structure and minor details without departing from the spirit or essential features thereof, still the preferred embodiment is shown in the accompanying drawings, in which:

Figure 1 is a side view of a farm wagon with the loader attachment in position and supporting a shock, a portion of the inner longitudinal bar of the main frame being 40 broken away to disclose the relative position of the supporting bar of the shock holder. Fig. 2 is a view similar to Fig. 1, the shock holder being turned into an approximately horizontal position and the shock resting 45 upon the ground, the parts appearing in the relative position which they will occupy either preliminary to lifting the shock or after the same has been deposited upon the ground. Fig. 3 is a detail perspective view 50 of the shock loader detached from the running gear, the rear axle of the latter being shown by dotted lines. Fig. 4 is a transverse section of the shock loader on the line x—x of

Fig. 1, the two positions of the operating or pinion shaft being shown by full and dotted lines. Fig. 5 is a top plan view of the shock holder.

Corresponding and like parts are referred to in the following description and indicated in all the views of the drawings by the same 60 reference characters.

In order to more fully comprehend the nature and application of the invention, the same is shown applied to the running gear of an ordinary farm wagon, said running gear 65 comprising the rear axle 1, front axle 2, rear bolster 3, front bolster 4, reach 5, rear hounds 6 and supporting wheels 7 which are fitted to the arms or spindles of the respective axles in the usual manner.

The shock loader comprises, essentially, two parts, a main frame and a shock holder. The main frame is supported in horizontal 70 position upon the running gear and comprises longitudinal bars 8 and cross pieces 9 and 10. 75

The rear cross piece 9 is set forward of the rear ends of the longitudinal bars 8 a short distance so as to rest upon the reach 5 and hound 6 and come in front of the rear bolster 3, while admitting of the rear ends of the 80 longitudinal bars 8 resting upon the rear bolster 3. A bolt 11 connects the rear cross piece 9 to the reach. The front cross piece 10 rests upon the front bolster 4 and is connected thereto by means of the king bolt 12. 85 Standards 13 are connected at their lower ends to the longitudinal bars 8 and are braced by means of stays 14. A windlass 15 is mounted in the standards 13 and is provided at one end with a gear wheel 16. An 90 operating shaft 17 is likewise mounted in the standards 13 both to turn freely and to have a limited longitudinal movement. The operating shaft is provided with a crank handle 18 and with a pinion 19, the latter being fast 95 thereto and adapted to have its teeth mesh with the teeth of the gear wheel 16, whereby upon rotating the operating shaft, the windlass 15 is turned to wind up the operating cord or cable 20 having connection therewith. A dog 21 pivotally mounted at one 100 end to a standard 13 is adapted to cooperate with the teeth of the pinion 19 and hold the windlass against backward rotation after the operating cord or cable has been subjected 105 to the requisite degree of tension. The op-

erating shaft is mounted to have a limited longitudinal movement to admit of throwing the teeth of the pinion 19 into and out of mesh with the teeth of the gear wheel 16, 5 this being of advantage when it is desired to release the windlass to admit of the cord or cable running freely therefrom to allow the shock or load to settle quickly upon the ground when it is required to discharge the 10 same. A plate 22 connects the standards 13 and is provided in one edge with a notch 23 to receive a portion of the crank handle 18 to hold the same stationary when the operating shaft 17 is moved to throw the pinion 19 out 15 of mesh with the gear wheel 16.

The shock holder comprises a confining frame, an impaling bar 24 and a supporting bar 25. The impaling and supporting bars are disposed approximately at a right angle 20 to each other and are braced by means of a stay 26. The confining frame comprises a cross head and upwardly or outwardly diverged bars 27. The cross head embodies spaced bars 28 which are connected by 25 means of end bars 29, which also are connected to the diverged bars 27 to strengthen and brace the same. Pivot supports 30 sustain the shock holder and consist of short bars which are adapted to be bolted or otherwise fastened to the running gear in any substantial manner. The impaling bar 24 and the supporting bar 25 are in the same plane and are centrally disposed with reference to the stays formed between the diverged bars 30 27, with the result that the weight of the load is equalized upon all parts of the shock holder and the main frame.

For lifting and securing the shock 31 or like load, sheave pulleys 32 are loosely connected to the upper or outer portion of the supporting bar 25 and end portions of the operating cord or cable 20 pass therethrough. The operating cord or cable is parted for convenience of passing the same about the 40 shock or load and the projecting end of the impaling bar and the separate ends are adapted to be connected by a suitable catch 33 or in any desired way. By having the sheave pulleys 32 loosely connected to the 45 supporting bar 25, they readily conform to the direction of strain upon the portions of the operating cord or cable, both in the confining of the shock and in the raising and lowering of the same.

50 From the foregoing it will be readily understood that a shock loader constructed in accordance with this invention may be readily applied to the running gear of a farm wagon and may be quickly and conveniently disconnected therefrom when not required for immediate use so as to be stowed away when using the farm wagon for general hauling. When the shock loader is in position

upon the running gear, the main frame is prevented from rearward displacement by 65 the rear cross bar 9 bearing against the rear bolster 3, thereby relieving the bolts 11 and 12 of the strain incident to raising and lowering of the load. The shock holder may be quickly placed in position and secured by 70 means of the pivot supports 30, which are bolted or otherwise fastened to the rear axle and rear bolster of the running gear. To take up a shock the loader is backed with the shock holder in horizontal position so as to 75 cause the impaling bar 24 to pass through the shock, after which the end portions of the operating cord or cable are passed about the shock and around the projecting end of the impaling bar and fastened. The windlass is 80 now operated so as to draw the shock and secure the same to the shock holder and cause the latter to turn from an approximately vertical position into a horizontal position, with the result that the shock assumes an approximately horizontal position above the main frame and running gear, as indicated most clearly in Fig. 1. When thus lifted the shock is transported to the place of discharge when it may be quickly deposited upon the 85 ground by throwing the operating shaft out of mesh with the windlass and turning the shock holder from a vertical into a horizontal position, the shock being deposited in an upright position upon the ground, as indicated most clearly in Fig. 2. Upon releasing the connected ends of the operating cord or cable and pulling upon the running gear, the 90 impaling bar is withdrawn from the shock and the latter left standing in the required 95 position.

It is to be understood that the component parts of the shock loader may be secured to the running gear of the vehicle in any convenient way depending upon the style and 105 make of the frame; also that the loader may be manipulated according to the idea of the operator. When it is required to deposit the shock upon the ground, the catch 33 may be tripped or disengaged in any way so as to release the holder and shock, after which the latter may be placed upon the ground by turning the impaling bar 24 from a vertical 110 to a horizontal position, thereby leaving the end portions of the cord or cable 20 hanging 115 loose from the sheave pulleys 32. When it is required to draw the cord or cable 20 from the windlass, the shaft 17 is moved to throw the pinion 19 out of mesh with the gear wheel 16, when a pull upon said cord or cable 120 will draw it freely from the windlass.

Having thus described the invention, what is claimed as new is:

In a shock loader, the combination of a main frame comprising longitudinal bars and 125 connecting cross pieces, the rear cross piece

being arranged forward of the rear ends of the longitudinal bars to come in front of the rear bolster of running gear and to permit the rear ends of the longitudinal bars resting upon the rear bolster, a shock holder pivotally connected to the running gear and comprising an impaling and a supporting bar, sheave pulleys applied to the supporting bar, an operating rope or cable having portions

passed through the sheave pulleys, and a windlass mounted upon the main frame and adapted to wind up the said cord or cable.

In testimony whereof I affix my signature in presence of two witnesses.

JOHN H. M. NIEMANN. [L. S.]
